(57) **CLAIM**

The ornamental design for an educational turntable toy, as shown and described.

DESCRIPTION

FIG. 1 is a front perspective view of an educational turntable toy, showing my new design in a first position;

FIG. 2 is a rear perspective view thereof;

FIG. 3 is a front perspective view thereof in a second position;

FIG. 4 is a front elevation view of FIG. 1;

FIG. 5 is a rear elevation view thereof;

FIG. 6 is an enlarged left side elevation view thereof;

FIG. 7 is an enlarged right side elevation view thereof;

FIG. 8 is a top plan view thereof; and,

FIG. 9 is a bottom plan view thereof.

The broken lines in the drawings illustrate the portions of the educational turntable toy, which form no part of the claimed design.
